HEAD ATTACHMENT FOR BANANA HAND TRUCK

Walter A. Reich, Kansas City, Mo., assignor to A. Reich & Sons, Inc., Kansas City, Mo., a corporation of Missouri

Application May 10, 1954, Serial No. 428,529

5 Claims. (Cl. 214—501)

This invention relates to improvements in equipment for handling bulky merchandise and has for its primary object the provision of a novel head designed to receive the loop of a hanging cord that is normally tied to the merchandise such as to the stem of banana bunches at the point of shipment from the plantation.

In my copending application, Serial No. 287,289, filed May 12, 1952, and now abandoned, the problems relating to expeditious handling of bunches of bananas by the wholesaler, from unloading through the ripening rooms, was initially set forth. A grappling hook adapted to grasp the aforesaid hanging cord and mounted on a vertically reciprocable, mobile hoist is therein disclosed as a solution to the task of moving the bunches to and from a position suspended from the ceiling hooks of the ripening room.

Subsequently, in my copending application, Serial No. 354,274, filed May 11, 1953, an extension of the program was disclosed, providing a hand truck employing the said grappling hook and adapted to facilitate unloading of the bunches. Through use of the hand truck the bananas could be moved into the ripening room and be received by the hoist of my first application.

On May 11, 1953, I filed my copending application, Serial No. 354,275, teaching how the hook of the said hand truck could be mounted on a vertically reciprocable hoist.

In each case, the grappling hook grasped the hanging cord between the loop thereof and the stem to which it was tied. It is difficult however, to transfer the bananas from the hand truck of Serial No. 354,274, to the grappling hook of Serial No. 287,289, or Serial No. 354,274, and at the same time leave the cord loop free to be received by the said ceiling hooks of the ripening rooms.

It is the most important object of the present invention therefore, to provide a novel head for hand trucks such as disclosed in my application Serial No. 354,274, this being a continuation-in-part of the aforementioned applications.

Another important object is to provide a head, as above set forth, having a shank provided with fingers for receiving the cord loop attached to the banana stem, thereby leaving the remainder of the cord free to be grasped by other suitable grapples.

Still another important object of this invention is to provide a head having spaced fingers that will not only receive the loop of a handling rope but will clear ceiling hooks or the like upon which the merchandise is hung or to be hung.

In the drawing:

Figure 1 is a side elevational view of a hand cart for carrying bananas, employing a loop-receiving head made according to my present invention.

Fig. 2 is an enlarged, top plan view of the head.

Fig. 3 is a cross-sectional view taken on line III—III of Fig. 2.

Fig. 4 is a fragmentary, side elevational view of the head.

2

Fig. 5 is a view similar to Fig. 4 showing the slide bar of the head locking the loop in place.

Fig. 6 is a perspective view of a modification of the present invention showing its manner of use in removing a looped rope from, or placing the same on a ceiling hook or the like.

Fig. 7 is an elevational view thereof showing the rope locked in place.

Fig. 8 is a bottom view thereof.

Fig. 9 is a section on line IX—IX of Fig. 8.

Fig. 10 is a section on line X—X of Fig. 9; and

Fig. 11 is a section on line XI—XI of Fig. 9.

Hand cart 10 shown in Fig. 1 is made according to the principles of my said application Serial No. 354,274, and includes a continuous, rectangular frame 12 having handle bars 14 to which are secured wheel means 16 to render the same mobile. A tubular lever 18, swingable on frame 12 upon release of latch means 20, has head 22, embodied in Figs. 1—5, rigidly secured thereto. The bunch of bananas 24, shown in Fig. 1 suspended from head 22, rests on a canvas panel 26 when the cart 10 is tipped back for rolling.

Stem 28 of banana bunch 24 is conventionally equipped with a hanging cord 30, usually tied thereon at the plantation and provided with a loop 32. Head 22 has been especially designed to receive the loop 32 as is also clear in Figs. 4 and 5.

Head 22 includes an elongated shank 34 extending into lever 18, as shown in Fig. 3, and provided with a longitudinal slot 36, open at its top exteriorly of lever 18. Slot 36 receives an elongated slide bar 38 for longitudinal reciprocation therein and retained in place by a stop bolt 40. A boss 42 on shank 34 has bolt 40 threaded therein, and a lock nut 44 on bolt 40 bears against boss 42. A notch 46 in the upper edge of bar 38 receives the lower end of bolt 40 which extends into slot 36.

Lower edge 48 of bar 38 slides on bottom wall 50 of U-shaped shank 36 and the edge slopes upwardly and forwardly at 52, terminating in a hook 54. A fingerpiece 56 projects downwardly below the inclination 52, presenting the hook 54.

The sides of shank 34 are notched at 58, clearing fingerpiece 56 for reciprocation, and have convex edges 60 extending upwardly and forwardly from wall 50, presenting a pair of fingers 62 that project beyond indentations 64. A bevelled, lowermost edge 66 on fingerpiece 56, is engageable complementally with upper edges 68 of fingers 62 as shown in Fig. 5.

With latch bar 38 open as shown in Fig. 4, cart 10 may be moved into position, and the lever 18 manipulated, after release of latch 30, to extend fingers 62 into loop 32 until the bight of the latter rests snugly with indentations 64. Thereupon, when bar 38 is closed, or permitted to slide closed upon tilting of shank 34 to the position shown in Fig. 5, loop 32 will be locked in place. Any tendency of loop 32 to slide out of the indentations 64 and along edges 68 of fingers 62 will only cause fingerpiece 56 to bear tighter against fingers 62 as loop 32 engages the hook 54.

When the bananas 24 are suspended from the head 22 as shown in Fig. 1, the entire hanging element 30 between fingers 62 and stem 28 is free to be grasped by any type of grappling hook, such as those hereinabove referred to. Conversely, when the bananas 24 are held suspended by a grappling hook in such manner, the loop 32 is held free for reception of the fingers 62 on head 22.

In presenting the embodiment of this invention shown in Figs. 6—11, only lever 118 of a cart or other handling equipment is illustrated, but the manner of use of the invention in connection with ceiling hooks 119 or the like can be better understood.

Head 122 includes an elongated shank 134 secured

rigidly to lever 118, and provided with a longitudinal slot 136 open at its top and bottom by virtue of the U-shaped configuration of shank 134 as seen in Fig. 8.

Slot 136 receives a bolt 140 that extends through a slot 137 in lever 118 and thence into an elongated slide bar or rod 138 within lever 118, bolt 140 serving to hold rod 138 against rotation in lever 118.

A plate or fingerpiece 156 on the outermost end of the rod 138 is provided with a V-shaped notch which forms an inwardly and downwardly inclined cavity 152 in rod 138, and presents a pair of shank-embracing legs 154.

The sides or legs of the shank 134 are notched at 158, clearing legs 154 for reciprocation toward and away from the proximal end of lever 118. Convex edges 160 extending upwardly and forwardly from the lower edges of shank 134 present a pair of fingers 162 that project beyond indentations 164. Inner edges 168 of fingers 162 slope downwardly and inwardly toward indentations 164.

Use and operation of head 122 is best understood by viewing Figs. 6 and 7. Lever 118 may be easily manipulated to and from a position extending fingers 162 through loop 132 and clearing hook 119. Note in Fig. 6 the way in which cavity 152 receives hook 119 so that fingers 162 may be moved to and from a position embracing hook 119 and receiving the bight of loop 132.

Assuming that loop 132 is being removed from hook 119, as soon as the bight of loop 132 is firmly seated in indentations 164 of fingers 162, lever 118 may be swung to lift the loop 132 clear of hook 119.

If, at any time lever 118 is swung to the position shown in Fig. 7, such as when lowering an article to which loop 132 is tied, bar or rod 138 will gravitate outwardly until legs 154 engage fingers 162, thereby locking loop 132 in place and preventing the same from slipping off fingers 162. Note in Fig. 11 that there is sufficient space between legs 154 and shank 134 to clear loop 132 when the latter is within indentations 164. But, if lever 118 is tipped downwardly still further from the position shown in Fig. 7 so that loop 164 moves out of indentations 164 and along edges 168, legs 154 will be embraced by loop 132 and the latter remains attached to head 122.

Rod 138 may be manipulated through use of fingerpiece 156 when needed or if desired, but for the most part, rod 138 slides automatically to and from the locking position shown in Fig. 7 as lever 118 is swung. If legs 154 happen to be in engagement with fingers 162 as hook 119 is approached, whether or not loop 132 is within indentations 164, rod 138 can be retracted as soon as the same engages the hook 119.

It is of course, understood that lever 118 may form a part of a cart or other equipment such as shown in Fig. 1. And, the operation of head 22 of Figs. 1-5 with respect to ceiling hooks and similar hanging means is the same as just described with respect to head 122.

Through use of these improvements therefore, the task of moving the banana bunch 24 or other heavy merchandise such as sides of beef and the like, to and from ceiling ropes, hooks or chains of ripening rooms, or the like, or hooks such as disclosed in my copending application Serial No. 315,456, filed October 18, 1952, is greatly simplified.

Having thus described the invention what is claimed as new and desired to be secured by Letters Patent is:

1. For use with equipment for handling bulky merchandise having a hanging element secured thereto, said element being provided with a loop normally suspended from a ceiling hook, a head including an elongated shank provided with an upwardly facing notch at one end thereof, presenting an extension, said shank having a slot subdividing the extension into a pair of spaced, upwardly and forwardly projecting, loop-receiving fingers adapted to extend into the loop and receive the hook therebetween

with the bight of the loop engaged over the extension; and a bar slidable to and from a position engaging the fingers, there being loop-receiving indentations in the fingers whereby the bar clears the loop when engaging the fingers, the uppermost edges of the fingers extending downwardly and inwardly at an angle as said indentations are approached.

2. For use with equipment for handling bulky merchandise having a hanging element secured thereto, said element being provided with a loop normally suspended from a ceiling hook, a head including an elongated shank provided with an upwardly facing notch at one end thereof, presenting an extension, said shank having a slot subdividing the extension into a pair of spaced, upwardly and forwardly projecting, loop-receiving fingers adapted to extend into the loop and receive the hook therebetween with the bight of the loop engaged over the extension; and a bar slidable to and from a position engaging the fingers, there being loop-receiving indentations in the fingers whereby the bar clears the loop when engaging the fingers, the uppermost edges of the fingers extending downwardly and inwardly at an angle as said indentations are approached, the bar being provided with a fingerpiece on one end thereof, said end being inclined upwardly and outwardly as said fingerpiece is approached.

3. For use with a hand truck for handling bunches of bananas wherein the bunches each have a hanging element secured to the stem thereof and provided with a loop, a head comprising an elongated shank provided

30 with a notch at one end thereof, presenting an extension, and a longitudinal, open top slot, said slot subdividing the extension into a pair of spaced, loop-receiving fingers; a bar slidable in the slot of the shank to and from a position engaging the fingers; and retaining means holding the bar within the slot, there being loop-receiving indentations in the fingers whereby the bar clears the loop when engaging the fingers, the uppermost edges of the fingers extending downwardly and inwardly at an angle as said indentations are approached, the bar being provided with a fingerpiece on one end thereof having an inclined, lowermost edge engageable with said edges of the fingers, said bar being provided with a lowermost edge having a portion inclined upwardly and outwardly as said fingerpiece is approached and spaced above the loop when said inclined edge of the fingerpiece is in engagement with the fingers, said fingerpiece extending downwardly below said inclined portion of the bar, presenting a loop-retaining hook when said inclined edge of the fingerpiece is in engagement with the fingers.

4. In a structure of the class described, a tubular handle; a slide bar extending into one end of the handle; a head on the handle having a pair of upstanding fingers extending beyond said one end of the handle; and a plate on the outermost end of the bar having a notch embracing the fingers, said notch having an uppermost apex end, there being a cavity in the plate and the bar extending inwardly and downwardly from said apex end of the notch.

5. In a structure of the class described, a tubular handle; a slide bar extending into one end of the handle; a head on the handle having a pair of upstanding fingers extending beyond said one end of the handle; and a plate on the outermost end of the bar having a notch embracing the fingers, said notch having an uppermost apex end, there being a cavity in the plate and the bar extending inwardly and downwardly from said apex end of the notch.
